MUFFLER FOR MONOXIDE GAS ELIMINATION

Julius C. Kittell, Sr., San Pedro, Calif.

Application November 28, 1940, Serial No. 367,485

1 Claim. (Cl. 181—43)

My invention relates to mufflers and more particularly to such devices which are especially adapted for collecting and for allowing the gases flowing therethrough to be mixed with incoming air and then allowing said mixed gases to gradually expand therein and thereby eliminating to a great extent the carbon monoxide gases and the smoke from said gases which are exhausted from the internal combustion engines.

Manifestly an object of my invention is to provide a suitable muffler means which is connected to the exhaust pipe of the internal combustion engine, said muffler means having suitable air inlet control member for allowing the air to enter therein and for mixing with said exhaust gases within said muffler, also having means for exhausting said mixed gases from said muffler silently and entirely and thereby eliminating the carbon deposits and the monoxide gases which are produced by the unburned hydrocarbons used in the operation of the internal combustion engines.

Therefore an object of my invention is to provide a suitably constructed muffler means having a conduit member for conducting the engine exhaust fluids into and through said muffler means, said muffler means having a suitably constructed Venturi tube means forming an orifice for drawing in and for diffusing the incoming air fluid with the volume of the incoming exhaust gases, also having an air volume controller and air diffuser member associated therewith for deflecting the air stream into said Venturi tube means for increasing its mixing capacity and when so mixed with a comparatively cold air thus causing a reduction of the gas pressure and in addition having a high velocity gas conduit member passing through said muffler means for drawing and for exhausting the mixed gases therefrom and thereby reducing considerably the carbon monoxide gases and the carbon deposits in said muffler means.

Other object of my invention is to provide said muffler means with an adjustable air inlet plate member which is provided with a plurality of adjustable baffle plate means for increasing or decreasing the volume of air passing into said muffler means and in addition which is adapted for deflecting said passing air at diversified angles and thereby increasing or decreasing the whirling effect of said air and the incoming exhaust gases which pass through said muffler means and therefore preventing the carbon deposits therein.

Further object of my invention is to provide

said muffler means with a suitable collector member having an intake and an exhaust passage, said intake passage having a suitable Venturi tube means associated therewith for drawing the cold air into said collector member and for mixing and expanding the passing gases therein, thereby producing a negative pressure in said collector member and for reducing the carbon monoxide contents in said mixed gases while passing through said collector member and at the same time silencing the gas discharge passing through the discharge passage of said muffler means.

Other and further objects and advantages of my invention as will hereinafter more fully appear, I attain by the construction herein shown on the drawing and described in the specification forming a part of my application.

Reference is had to the accompanying drawing in which the similar reference characters denote the similar parts.

In the drawing:

Fig. 1 is the longitudinal sectional view of the muffler showing the relative position of the air intake and the air control member, also having the Venturi tube positioned therein in close proximity to the gas inlet passage, also showing the position of the high velocity tube in relation to the inlet passage and the exhaust passage of the apparatus.

Fig. 2 is the vertical sectional view of the muffler showing the elevational view of the baffle plates in relation to the air apertures, taken on the line 2—2 of the Fig. 1.

Fig. 3 is the vertical sectional view of the muffler showing the front elevational view of the Venturi tube and the gas intake passage, taken on the line 3—3 of the Fig. 1.

Fig. 4 is the vertical sectional view of the muffler showing the end elevational view of the spider member adapted for holding the high velocity tube member in place and within the muffler housing, taken on the line 4—4 of the Fig. 1.

Fig. 5 is the vertical sectional view of the muffler showing the elevational view of the exhaust passage and in relation to the high velocity tube, taken on the line 5—5 of the Fig. 1.

Describing my invention more in detail said invention comprises a muffler generally designated by numeral 2, which consists of a tubular housing member 4 having an intake end 6 and the discharge end member 8.

Said intake end 6 is provided with a suitable air controller plate 10 which is equipped with a

suitable flange 12 for connecting same thereto as shown, having its center provided with the gas intake pipe 14 and also having its mid-section 16 provided with a plurality of apertures 18, each of which is equipped with an individual deflecting plate member 20.

The intake pipe 14 extends inwardly and into said housing member 4, having its end 22 in line and in position with the edge 24 of the Venturi tube member 26, it being made an integral part of the plate member 28 of which its edge is provided with a suitable flange 30 for connecting and for mounting same in place and within said housing member 4, so that the passing gases, as at 32 will draw the air through the restricted orifice 34 from and through the apertures 18 of said controller plate 10.

Internally in said housing member 4 and extending approximately between the intake end 6 and the discharge end 8, a suitable high velocity tube 36 is positioned which is held in place by means of spider members 38 and which are connected to said housing member 4 as shown, having the intake end 40 of said high velocity tube 36 placed partially within the end 22 of said intake pipe 14, while its discharge end 42 is positioned slightly to the rear of the orifice 44 formed at the exhaust pipe 46 for forming a gas convection while the apparatus is in operation.

For holding said exhaust pipe 46 in place and position, it is made an integral part of the end plate member 48, having a suitable flange 50 for connecting same to the discharge end member 8.

In operation, the exhaust gases passing from the internal combustion engine enter the muffler 2 and the housing member 4 through the gas intake pipe 14 and continuing in its passage through the high velocity tube 36 and discharging a portion of said gases into the exhaust pipe 46.

At the orifice 34 said passing gases form a partial vacuum which draw the air passing through said apertures 18 and due to the angular position of said deflecting plate members 20 said air changes its course of travel and forms a spiral whirl within said housing member 4 which greatly increases its mixing effectiveness with the incoming exhaust gases, further, due to an extremely rapid change of temperature the gases expand instantaneously and thereby reduce the gas pressure within said housing member 4.

Said expanded gases collected in said housing member 4 are then drawn through and into said exhaust pipe 46 by means of fluid convection caused by the high velocity gas discharge through the discharge end 42 of said high velocity

tube 36 at the orifice 44 of the exhaust pipe 46 and thereby discharging the exhaust gases through said apparatus greatly minimized in percentage and the contents of said carbon monoxide gases and also reducing considerably the carbon deposits in said housing member 4.

In practice it has been found that the most satisfactory proportions of the exhaust gases and the air at the restricted orifice 34 is at 50% per volume taking into consideration the internal diameter of the high velocity tube 36 which draws only 5% of the discharged gas volume passing through the intake pipe 14 from the internal combustion engine, and that in the Diesel fuel engines, said proportions may be adjusted in accordance with the efficiency of the fuel jets and by increasing the diametral size of the Venturi tube member 26 including the area of the apertures 18.

While I have thus described my invention with great particularity it will be clear that the same may be modified throughout a wide range.

I accordingly do not propose to be limited to the exact details of construction herein shown on the drawing and described in the specification, but reserve the right in practice to make the necessary changes and modifications therein which may come within the scope of the appended claim.

I claim as my invention:

A muffler of the class described adapted for use in connection with internal combustion engines, comprising a housing having a gas inlet tube and a discharge pipe, an air controlling plate positioned at the inlet end of said housing having said gas inlet tube passing therethrough, a gas inlet tube end disposed in said housing, a plurality of apertures disposed in said air controlling plate for permitting said air to enter into said housing, a baffle plate connected to each of said apertures for deflecting said passing air and for whirling said air while passing through said housing, a Venturi tube means mounted within said housing having its orifice at the end of said gas inlet tube for drawing and for mixing said gas and said air passing therethrough, and a high velocity tube means centrally positioned in said housing having its inlet end positioned in the center of said gas inlet tube end and the exhaust end positioned at said discharge pipe for creating a gas convection and thereby discharging said mixed gases from said housing, substantially as described.

JULIUS C. KITTELL, Sr.
